(57) **CLAIM**

The ornamental design for a wearable soaking garment, as shown and described.

DESCRIPTION

FIG. 1 is an isometric view of a wearable soaking garment showing my new design;

FIG. 2 is front side view thereof;

FIG. 3 is a rear side view thereof;

FIG. 4 is a right side view thereof;

FIG. 5 is a left side view thereof;

FIG. 6 is a top side view thereof;

FIG. 7 is a bottom side view thereof;

FIG. 8 is a right side view of the wearable soaking garment in a first position when worn thereof; and,

FIG. 9 is front side view of the wearable soaking garment in a second position when worn thereof.

The broken lines shown in FIGS. 8 and 9 illustrate environment and form no part of the claimed design.
